(57) **CLAIM**

The ornamental design for a toy construction cell component, as shown and described.

DESCRIPTION

FIG. 1 is a top perspective view showing the toy construction cell component;

FIG. 2 is a bottom perspective view of FIG. 1;

FIG. 3 is a top side view of FIG. 1;

FIG. 4 is a bottom side view of FIG. 1;

FIG. 5 is a front side view of FIG. 1, the back side view being an opposite mirror image thereof; and,

FIG. 6 is a right side view of FIG. 1; the left side view being an opposite mirror image thereof.
